UNITED STATES PATENT OFFICE.

LOUIS WULKAN, OF CEDARHURST, NEW YORK.

MOUNTING FOR RADIO LOUD SPEAKERS.

Application filed November 12, 1925. Serial No. 68,737.

This invention relates to an amplifying device for use with radio receiving sets, known as "loud speakers". The object of this invention is to provide an improved device of this nature, particularly applicable to the "cone-type loud speaker".

The features of the invention here involved have to do more especially with the method or means provided for supporting the loud speaker unit, which latter may be of the usual construction, so far as its operating parts are concerned, and by reason of the novel means provided many advantages are obtained not heretofore possible with the usual mounting means and arrangement.

With this object in view, I have provided a mounting device which is provided with a base, adapting it to be placed upon a table, etc., and two vertical supports attached at opposite sides of the base. At the top and carried by these vertical supports is a circular member to which a cone-shaped vibratory member is attached, this cone-shaped member being connected to and operated by a loud speaker unit in the usual manner. The construction and operation of this cone-shaped member and loud speaker unit does not, per se, form a part of my invention, which has to do with the method and means provided for supporting the same in a horizontal position instead of in the usual vertical position with a support at one edge only.

Among the advantages found by mounting the cone and its operating unit in a horizontal position is that the same is more generally non-directional in sending out the sound waves. Whether these waves are thus projected as "horizontal waves" or not, I have not determined, but I have found an improved quality of the tone produced when my arrangement is used over that produced by the usual vertical mounting of the cone. Furthermore, with my arrangement, the device may be made very ornamental in appearance, which is a desirable feature in the present development of devices of this nature.

On account of the double support for the cone, greater rigidity is secured and the device is very substantial in construction. This makes it possible to readily adapt the loud speaker for use as the base element for a table lamp, which may be readily attached thereto without interfering with the operation of the loud speaker unit.

In the drawings accompanying this appli-

cation, I have shown one embodiment of my invention and in the description of the several details of the same the above noted and other objects and advantages will be apparent.

Fig. 1 is a top plan view of a device illustrating an embodiment of my invention as applied to a loud speaker unit of the cone type.

Fig. 2 is a side elevation of Fig. 1.

A base is indicated at 1, which may be of any suitable size or shape and arranged to rest upon a table or other article of furniture, as desired. Two vertical supports, 2 and 3, are attached at opposite sides of the base 1. The supports may be of suitable ornamental design, as desired.

A circular member 4 is mounted in a horizontal position on top of the two vertical supports 2 and 3. This circular member is relatively rigid in construction. A cone-shaped vibratory member 5 is mounted at its edge upon the circular member 4 and is connected with a loud speaker unit, indicated at 6, in the usual manner. That is, the cone-shaped vibratory member and loud speaker unit may be of the usual construction, but with the difference that the cone is mounted in a horizontal position and carried upon two vertical supports at its opposite edges.

One of the vertical supports is provided with a longitudinal opening extending therethrough, through which opening the wire connections to the loud speaker unit 6 may be led. Suitable channels are also provided in the base 1 for bringing these wire leads to the outer edge of the base for connection to the receiving set, as indicated at 7.

In order to provide a more substantial construction, a metal tube 8 may be positioned in the longitudinal opening in the vertical support, its ends extending through the base, at the lower end, and through the circular member 4 at the upper end and nuts 9 and 10 threaded on each end, thus firmly securing the several parts together. It will be understood that the construction of the opposite vertical support 2 is similar to that described for the support 3, including the metal tube and nuts securing the parts together at this side also. This also provides for mounting a lamp bracket, of any desired design, at the upper end of the support 2, the wires for the lamp being

brought through the vertical support 2 in a similar manner.

It will be seen that by providing the horizontal mounting of the loud speaker unit 5 and cone and two supports at opposite sides it is possible to combine the loud speaker with a table lamp in a practical manner in 10 a unitary device which is very substantial in construction and without destroying any 15 of the properties of the loud speaker but, in fact, improving the operation.

What I claim as new and desire to secure by Letters Patent is:—

1. In a device of the class described, in 15 combination, a base, vertical supports attached to opposite sides of said base, a circular member carried in a horizontal position by said vertical supports, and a cone-shaped vibratory member supported horizontally by said circular member adapted 20 for connection with a loud speaker unit.

2. In a device of the class described, in 25 combination, a base, vertical supports attached to opposite sides of said base, one of said supports being provided with a longitudinal opening therethrough, a circular member carried in a horizontal position by said vertical supports, and a cone-shaped vibratory member supported horizontally by 30 said circular member adapted for connection with a loud speaker unit.

3. In a device of the class described, in combination, a base, vertical supports each provided with a longitudinal opening there-

through and attached to opposite sides of 35 said base, a circular member carried in a horizontal position by said vertical supports, and a cone-shaped vibratory member supported horizontally by said circular member adapted for connection with a loud 40 speaker unit.

4. In a device of the class described, in combination, a base, vertical supports each provided with a longitudinal opening therethrough, 45 a circular member horizontally mounted upon said supports and secured thereto, a metal tube positioned in each of said longitudinal openings in said vertical supports and extending through said base at one end and through said circular member and provided with fastening means at each end securing said members together, and a cone-shaped vibratory member carried in a horizontal position by said circular member and adapted for connection with 50 a loud speaker unit.

5. In a device of the class described, in combination, a base, vertical supports attached at opposite sides of said base, and a cone-shaped vibratory member adapted 55 for connection with a loud speaker unit and supported at opposite sides thereof in a horizontal position by said vertical supports.

Signed at New York, in the county of New York and State of New York this 10 60 day of Nov. A. D. 1925.

LOUIS WULKAN.
